CLAIM

The ornamental design for a domestic carbonated drink preparing device, as shown and described.

DESCRIPTION

FIG. 1 is a top isometric view of a domestic carbonated drink preparing device with a tray at an extended position, showing our new design;

FIG. 2 is a front view thereof;

FIG. 3 is a back view thereof;

FIG. 4 is a left side view thereof, the right side view being a mirror image;

FIG. 5 is a top view thereof;

FIG. 6 is a bottom thereof;

FIG. 7 is a top isometric view thereof with the tray at a folded position;

FIG. 8 is a top isometric view of a second embodiment of the domestic carbonated drink preparing device with the tray at an extended position;

FIG. 9 is a front view thereof;

FIG. 10 is a back view thereof;

FIG. 11 is a left side view thereof; the right side view being a mirror image;

FIG. 12 is a top view thereof;

FIG. 13 is a bottom view thereof; and,

FIG. 14 is a top isometric view thereof with the tray at a folded position.

Elements drawn in broken lines in FIGS. 8-14 represent portions of the domestic carbonated drink preparing device that form no part of the claimed design.

1 Claim, 13 Drawing Sheets
